The ornamental design for a bottle, as shown and described.

DESCRIPTION

FIG. 1 is a front perspective view of a first embodiment of a bottle showing my new design;

FIG. 2 is a side view thereof;

FIG. 3 is the other side view thereof;

FIG. 4 is a rear view thereof;

FIG. 5 is a front view thereof;

FIG. 6 is a top plan view thereof;

FIG. 7 is a front perspective view of a second embodiment of a bottle showing my new design;

FIG. 8 is a side view thereof;

FIG. 9 is the other side view thereof;

FIG. 10 is a rear view thereof;

FIG. 11 is a front view thereof; and,

FIG. 12 is a top plan view thereof.

The dashed broken lines in the Figures are included for the purpose of illustrating portions of the bottle that form no part of the claimed design. The vertically oriented dot-dashed line indicates the boundary of the claim adjacent the shaded and solid line portions of the bottle. The dot-dashed line likewise forms no part of the claim.
